(57) **CLAIM**

The ornamental design for a stand with surgical microscope, as shown and described.

DESCRIPTION

FIG. 1 is a perspective view of the stand with surgical microscope;

FIG. 2 is a right side elevation view of the stand with surgical microscope;

FIG. 3 is a left side elevation view of the stand with surgical microscope;

FIG. 4 is a bottom plan view of said stand with surgical microscope;

FIG. 5 is a front elevation view of said stand with surgical microscope;

FIG. 6 is a rear elevation view of said stand with surgical microscope; and,

FIG. 7 is a top plan view of said stand with surgical microscope.

In FIG. 4, the elements adjacent the stand, the bottom portion of the stand and the central portion of the casters shown in broken lines form no part of the claimed design.
